UNITED STATES PATENT OFFICE.

EDWARD T. HUDSON, OF SUPERIOR, NEBRASKA.

RURAL MAIL CARRYING AND DELIVERING DEVICE.

1,284,348.

Specification of Letters Patent. Patented Nov. 12, 1918.

Application filed March 26, 1918. Serial No. 224,797.

To all whom it may concern:

Be it known that I, EDWARD T. HUDSON, a citizen of the United States, residing at Superior, in the county of Nuckolls and

5 State of Nebraska, have invented certain new and useful Improvements in Rural Mail Carrying and Delivering Devices; and I do hereby declare the following to be a full, clear, and exact description of the invention, such as will enable others skilled in the art to which it appertains to make and use the same.

10 My invention relates to mail carrying and delivering devices of that type suspended upon cables or tracks and capable of delivering mail boxes, receptacles or the like at each rural station along a rural route.

15 Another object of this invention is the provision of a rural mail carrying and delivering device of the above stated character especially adapted to deliver a mail box, receptacle or the like at each rural station and pick up an empty box, receptacle or the like which has been previously delivered.

20 25 A further object of this invention is to provide an automatic mailbox or receptacle releasing device which, when the device reaches each station, will be so actuated as to release one of the mailboxes at the station.

30 35 A still further object of this invention is to provide a device of this character, which will be simple, practical and comparatively inexpensive in construction, and one that can be manufactured and sold at a low cost.

With these and other objects in view, the invention consists in the novel combination and arrangement of parts hereinafter more 40 fully described and set forth in the claims hereto appended.

In the drawings:

Figure 1 is a side elevation of a rural mail carrying and delivering device as made in 45 accordance with this invention.

Fig. 2 is a top plan view of the rural mail carrying and delivering device.

Fig. 3 is a rear elevation of the device.

Fig. 4 is a vertical transverse sectional 50 view taken on the line 4—4 of Fig. 1.

Fig. 5 is a detail side elevation illustrating the box, receptacle or the like, releasing device.

Fig. 6 is a vertical transverse sectional 55 view taken on the line 6—6 of Fig. 1 and looking in the direction indicated by the arrows.

Fig. 7 is a side elevation of the track supporting post which is adapted to be located at each and every station along the rural route.

Like numerals of reference designate corresponding parts in all the figures of the drawings.

Referring to the drawings, the numeral 5 indicates a supporting post which is adapted to be embedded at each station along the rural route. The post 5 has secured adjacent its upper end and extending horizontally therefrom an arm 6, which arm is held against displacement from the post by the diagonal brace 7 which is secured to the post and arm respectively by its respective ends. An inverted T-shaped supporting member 8 is secured by the terminal of its stem to the under side of the arm 6 centrally thereof and the head of this T-shaped supporting member has its terminals curved upwardly as at 9 to provide track flange engaging members. A removable flange engaging member 10 is secured to the head 9 at a spaced distance from each upturned end and these members 10 and 9 are adapted to rigidly support the track 11 thereto. The track 11 on the outside of the stem 8 is adapted to constitute the outgoing track, while the other track is adapted to constitute the incoming track and on which my mail carrying device is adapted to be suspended, whereby mail may be delivered along the rural route.

The heretofore described tracks may be constructed from ordinary rails as illustrated clearly in the drawings or may be of stout wire or cable secured to the T-shaped members in any well known manner.

The mail carrying and delivering device is indicated as a whole by the numeral 12 and it comprises a frame consisting of a pair of relatively spaced angle bars 13. The rear end of each bar has depending therefrom a vertical bar 14. A shaft 15 is rotatably journaled in said vertical bars in the lower terminal thereof.

The shaft 15 has secured centrally thereto a stop lever 16 which is normally held in a vertical position until the shaft is rotated.

A diagonal brace bar 17 has one end secured to the lower end of each bar 14 and the free ends of these rods are secured to the lower edge of the vertical flange of the angle bars 13 to reinforce and strengthen the frame at the rear end thereof. The bars

13 are connected at their forward ends by a brace 18 which has its medial portion depressed to form a seat 19 for an operating motor 20. The upper member of the motor frame 5 has formed centrally thereon a shank 21 the terminal of which is bent laterally and extends beyond the outer side of the track 11 and this laterally extending portion is bent upwardly to and beyond the track 11 to provide a wheel supporting bracket 22.

A groove wheel 23 is journaled in the bracket 22 and is adapted to engage the track to support the forward end of the frame thereto. The shaft upon which the groove wheel is journaled extends laterally beyond the exterior of one side of the bracket 22 and has secured thereon a drive wheel 24. The drive wheel 24 is located in direct alinement with the drive wheel 25 located on the motor shaft 26, which motor shaft is rotated by the motor 27 located in the frame 20. A belt 28 is trained over the pulley wheels 24 and 25 and upon the energization of the motor 27 the wheel 25 will be rotated in turn rotating the wheel 24 to cause the rotation of the groove wheel 23 upon the track 11 to cause the mail delivering frame to move forwardly thereon, the purpose of which will be hereinafter more fully described.

It will be understood that the motor is adapted to be connected with a suitable electric source designated 29 which is in circuit with the track 11.

To support the rear end of the frame upon the track 11, I provide a plurality of mail receptacles, boxes or the like 30 and as each and every one of the boxes are identical the description of one will serve for all. The box 30 has an upper open end and has secured thereacross a brace arm 31 which has formed centrally therefrom an upstanding bracket 32 identical in construction with the bracket 22 carried by the motor. A groove wheel 33 is journaled in the upper portion of the bracket 32 and is adapted to engage the track 11 to retain the rear portion of the frame in horizontal alinement and coöperate with the motor supporting frame to retain the frame in position upon the tracks. Secured to and extending laterally from the bracket 32 at the lower portion thereof are the arms 33' each having journaled to its outer end a roller 34' which is adapted to run upon the upper side of the spaced angle bars 13. Formed on and extending laterally from each side of the box or receptacle 30 at the upper end thereof is a shaft 34 having journaled on its outer end a wheel 35 for engagement with the under side of the horizontal flanges of the spaced angle bars 13, thus preventing the boxes from being moved vertically in the frame.

It will be understood that a plurality of

these mail boxes or receptacles or as many boxes or receptacles are supported by the frame as there are stations along the rural route. The rear mail box is adapted to be engaged by the stop 36 to prevent it from being urged from the frame during its travel over the track. It will also be apparent that upon the energization of the motor the frame will start moving on its track to and in the direction of the first station, which is designated by a post 5.

The diagonal brace bars have secured centrally thereto and extending laterally therefrom stub shafts 36' and rotatably mounted on the outer end of each stub shaft 36' is a grooved drum 37. A ratchet wheel 38 of a diameter less than the drum is secured to one of the drums on the inner side thereof for rotation therewith. The teeth of the ratchet wheel 38 are adapted to be engaged by a pawl 39 which is pivotally secured as at 40 to a drum operating lever 41, which lever is pivotally secured to the shaft 15 at its lower end. The upper end of the lever 41 extends upwardly beyond the frame 12 and is adapted to engage the arm 6 of each post so as to operate said drum and to also release the rear mail bag, box or the like. A spring 42 has one end secured to the operating lever 41 and its opposite end secured to the pawl 39 to normally retain the pawl in engagement with the teeth of the ratchet wheels 38 so that the ratchet wheel will be returned upon the rearward movement of the operating lever 41 to its initial position.

An arm 43 has one end pivotally secured as at 44 to the operating lever 41 adjacent its upper end. The free terminal of this arm has a concave bearing member formed thereon for engagement with the roller 34' of each mail box 30 upon forward movement of the arm so that as it engages the arm 6 of the post 5 it will urge the rear mail bag out of the frame and thus leave it at its destination.

A cable 46 is secured to each grooved drum 37 at one end, and the free ends of these cables are secured as at 47, to the arms 48 which extend laterally from the opposite sides of the cable supporting member 49. The cable supporting member 49 has journaled therein a groove wheel 50 for engagement with the track to support the same thereto. The lower end of the member 49 is substantially rectangular and is adapted to engage the foremost mail box, bag or the like, and upon the actuation of the operating member 41 the bag will be urged rearwardly and another bag will take the place of the bag displayed at its proper destination.

In use, the mail boxes 30 are filled with the mail for the proper destinations, the motor is energized and the frame started on its

outward travel upon the outgoing track 11. Upon reaching the first station along the rural route, the operating arm 41 strikes the arm 6 of the post at that station moving the same rearwardly thus urging the arm 43 into engagement with the roller of the last mail box urging the same outwardly off of the frame, it being understood that by movement of the arm rearwardly, the 10 stop member 16 is thrown downwardly to permit of this operation. After the mail bag has been delivered and the machine has passed beyond the post, the operating arm 41 returns to its initial position during 15 which movement the ratchet wheel is given one-eighth revolution by the pawl 39 rotating the drum which winds the cable thereon, thus moving the bags or boxes rearwardly for placing another box in position 20 to be delivered at the next station.

It will be understood that the mail boxes, receptacles or the like left on the first outgoing trip at each rural station, designated by one of the posts 5, will be picked up on 25 the return trip by the frame carrying the motor. The frame carrying the motor will take up the first bag and so on until it has collected all of them and will push the empty receptacles ahead of it until it reaches 30 the starting point again.

Having thus described my invention what I claim is:

1. A device of the class described including a frame, a motor at the forward end of 35 the frame, drums journaled adjacent the rear end of the frame, a suspended track, means for supporting the frame upon the track, and a plurality of mail receptacles supported by the frame and track, and 40 means carried by the frame for automatically releasing each of the mail receptacles.

2. A device of the class described including a frame, a motor carried at the forward end of the frame, drums journaled adjacent 45 the rear end of the frame on the exterior thereof, a track, means carried by the motor and adapted to rotatably engage the track for supporting the forward end of the frame, a plurality of mail receptacles, means 50 rotatably supporting the mail receptacles to the track and upon the upper side of the frame, cable supporting means, said cables adapted to be wound upon the drums, and means connected to one of said drums for 55 automatically releasing one of the mail receptacles at different intervals for urging the adjacent receptacle in the direction of the rear end of the frame, as and for the purpose specified.

60 3. A device of the class described including a frame, a suspended track, a motor carried by the forward end of the frame, means for rotatably supporting the forward

end of the frame upon the track, a plurality of mail receiving receptacles rotatably mounted in the frame, means carried by each receptacle and adapted to be rotatably mounted upon the track for supporting the rear end of the frame, drums journaled to the frame, cable supporting means rotatably mounted upon the track, cables secured to said means, the free end of said cables wound about said drums, and means carried by one of said drums and adapted to be operated by track supporting means to release one of the mail bags or boxes and rotate the drums to move the adjacent mail receptacle rearwardly on the frame.

4. A device of the class described including a frame, a motor supported at the forward end of the frame, drums journaled adjacent the rear end of the frame, a suspended track, means for supporting the frame upon the track, and including a plurality of mail supporting receptacles and 80 frame for supporting the motor, and means carried by the said first frame for automatically releasing each of the mail receptacles at points along a rural route.

5. A device of the class described including a frame, a motor supported at the forward end of the frame, drums journaled adjacent the rear end of the frame on the exterior thereof, a plurality of mail receptacles, means for supporting the mail receptacles on the frame, said mail receptacles and 95 motor adapted to support the frame upon a track, and means supporting the track whereby the mail receptacles may be released automatically and independently from the 100 frame at points along a rural route.

6. A device of the class described including a frame, a suspended track, a motor at the forward end of the frame, means carried by the motor for engaging the track to support the forward end of the frame thereto, drums journaled adjacent the rear end of the frame, a plurality of mail receptacles rotatably supported upon the frame and track, drums journaled on the frame, cable 105 supporting means carried by the frame, and track, said cables adapted to be wound upon the drums, means carried by the drums for automatically disengaging each mail receptacle independently from the frame at 110 points along the rural route and to wind the drums to urge the adjacent mail bag or receptacle in position to be released from the frame.

In testimony whereof I affix my signature in presence of two witnesses.

EDWARD T. HUDSON.
